R. SPERRY.
PUMP JACK,
FILED MAY 22, 1922.

27a Inventor
Raymond Sperry,

Geo. P. Kimmel
Attorney

UNITED STATES PATENT OFFICE.

RAYMOND SPERRY, OF PRUE, OKLAHOMA.

PUMP JACK.

Application filed May 22, 1922. Serial No. 562,738.

To all whom it may concern:

Be it known that I, RAYMOND SPERRY, a citizen of the United States, residing at Prue, in the county of Osage and State of Oklahoma, have invented certain new and useful Improvements in Pump Jacks, of which the following is a specification.

The invention relates to a pump rod operating jack, and more particularly to the class of walking beams and operating mechanism for actuating oil well pumps.

The primary object of the invention is the provision of a mechanism of this character, wherein the walking beam is supported in a novel manner and is constructed and arranged to withstand heavy loads, the pump rod being readily attached to and removed from the operating end of the walking beam, while connected to the opposite end of said beam is operating mechanism, which also is novel in form so that the said beam can be readily rocked for actuating the pump rod.

Another object of the invention is the provision of mechanism of this character, wherein minimum power is required for actuating the pump jack including the walking beam connected with the pump rod.

A further object of the invention is the provision of mechanism of this character, wherein the support or fulcrum for the walking beam is constructed, arranged and mounted relative to a foundation or platform so that it can be properly adjusted for the alinement of the pump rod within the well cap, the walking beam, swingingly connected to the support, is of novel form so as to permit the operating mechanism to be conveniently attached to and removed therefrom, this also being true of the pump rod, said walking beam being also adjustable relative to its support so as to vary the leverage of the operating mechanism therefor. A still further object of the invention is the provision of mechanism or jack of this character, which is extremely simple in construction, thoroughly reliable and efficient in its purpose, readily and easily set up for use, and inexpensive to manufacture and install.

With these and other objects in view, the invention consists in the features of construction, combination and arrangement of parts, as will be hereinafter fully described, illustrated in the accompanying drawing, and pointed out in the claims hereunto appended.

In the accompanying drawing:—

Figure 1 is a side elevation of the pumping mechanism or jack constructed in accordance with the invention, one of the braces for the support for the walking beam being partly broken away.

Fig. 2 is a top plan view thereof.

Fig. 3 is an end elevation.

Fig. 4 is a fragmentary perspective view of the rocking lever and connections of the operating mechanism for the walking beam.

Similar reference characters indicate corresponding parts throughout the several views in the drawing.

Referring to the drawing in detail, A designates a well cap, which is of the ordinary well known construction or of approved type through which works the pump rod B, the latter at its upper end being formed with a cross or T-head C, for the detachable connection thereof with the walking beam of the pump jack hereinafter fully described.

Positioned in proximity to the well cap A, as well as being supported or secured in any suitable manner upon the foundation or ground, is a base or platform consisting of a pair of spaced longitudinally extending beams 5, arranged in parallelism, and which are joined together at the ends thereof through the medium of horizontally disposed end cross pieces 6, 6'. The beams and cross pieces are connected together in any suitable manner to provide a unitary structure.

Secured to the upper face of the cross piece 6, near each end thereof, by the hold-fast devices 7', is a bearing 7, and journaled in the bearing 7, are outwardly extending trunnions 8, integral with the lower ends of the side arms of an inverted U-shaped support 9. Adjustably mounted on the top of the support 9, is a walking beam 10, to be hereinafter more fully described.

Secured to the lower face of the beam 10, centrally thereof, by the hold-fast devices 10', is a saddle 11, which is formed medially thereof and in its lower face with a plurality of spaced transversely extending grooves or notches 23, which provide seats for the top of the support 9, and by this arrangement the beam 10, can be adjustably supported lengthwise relative to the support 9.

Secured to the upper face of the beam 10, centrally thereof, by the hold-fast devices

12', is a vertically disposed bridge piece 12, over which is extended a truss rod 13, the latter inclining downwardly from its center toward each end. Secured to the upper face 5 of the beam 10, at one end thereof, by the hold-fast devices 14' is a bracket 14, and secured to the upper face of the beam 10, at the other end thereof, by the hold-fast devices 15' is a bracket 15. Each of the 10 brackets 14, 15, is provided at its inner end with an upwardly extending and inwardly inclined arm 15^b, and to the said arms 15^b, the ends of the truss rod 13, are secured by the hold-fast devices 15^c. The beam 10, at 15 that end carrying the bracket 14, as well as the latter, is bifurcated for the reception of the upper end of the pump rod B. The outer end of the bracket 14, is formed with an upwardly extending hook 16, to receive 20 the cross or T-head C, at the upper end of the pump rod B, as shown in Figures 1 and 2 of the drawings. The bracket 15, projects outwardly from that end of the beam 10, to which it is secured, and the extended portion of the bracket 15, is formed 25 with a downwardly extending hook 17, in which is detachably mounted the upper end of an inverted U-shaped connector strap 18, having its lower ends looped, as at 19, for connection with the beam operating mechanism to be hereinafter referred to.

Carried by the cross piece 6, is a U-shaped anchor 20, to which is pivotally connected the lower ends of spaced inclined 35 brace rods 21, which have their upper ends pivotally connected, as at 22', to clamps 22, secured upon the side arms of the support 9, for maintaining the latter in an upright position when supporting the beam 10.

40 To prevent the lateral displacement of the beam 10, on the top of the support 9, a pair of spaced stops is secured thereto and arranged one at each side of the beam 10, as clearly shown in Figure 2. Secured to 45 each of the beams 5, intermediate its ends by the hold-fast devices 25', is a bearing 25, and in the bearings 25, is journaled a stub shaft 26, which constitutes a pivot for a substantially triangular shaped rocking 50 lever comprising a vertically disposed inner arm 27, a pair of outwardly extending spaced parallel lower arms 27^a formed integral with and disposed at right angles with respect to the lower end of the arm 27, an 55 inclined outer arm 27^b, having a looped lower end 27^c, through which extends a pivot pin 27^d, for connecting the arm 27^b, to the rear ends of the arms 27^a. The upper end of the arm 27^b, is looped, as at 27^e, and 60 merges into the upper end of the arm 27.

The shaft 26, extends through the arms 27^a, in proximity to the lower end of the arm 27. The pivot pin 27^d, has its ends projecting from the arms 27^a.

65 Connected to the looped end 27^e of the

arm 27^b, is the looped end 28^a, of an operating rod 28, and pivotally connected to the projecting ends of the pivot 27^d, are the lower ends of the connecting straps 29, which have looped upper ends 29^a, for attachment to the looped lower ends 19 of the connector strap 18.

It will be apparent from the foregoing construction and arrangement of elements, 75 that on reciprocation of the rod 28, the triangular shaped lever will be rocked on its shaft 26, and through the connection between said lever and the walking beam, the latter will be oscillated on the support 9, causing thereby the reciprocation of the 80 pump rod B, within the well.

The arm 27, of the triangular shaped rocking lever is provided with an eye 30, which is adapted to be engaged by a latching hook 31, for locking the lever from 85 movement. The latching hook 31, is mounted on the cross piece 6, between the side arms of the support 9.

Carried by the other cross end piece 6 of the base or platform 5 is a U-shaped anchor 90 20 to which are pivotally connected the braces 21, the same being also pivotally connected to clamps 22 mounted upon the limbs of the inverted U-shaped support 9 so that in this manner the latter is held in upright 95 position for the carrying of the walking beam. The saddle 11 of the walking beam 10 medially thereof is formed with plural transverse notches 23, constituting seats for the upper closed portion of the support 9 and 100 in this manner the said walking beam 10 can be adjusted relative to the support as will be clearly obvious from Fig. 1 of the drawing.

The support 9 is fitted in its top cross bar 105 with stops 24 to prevent any lateral displacement of the walking beam 10 thereon.

Mounted on the longitudinal beams 5 of the platform or base at an intermediate point are bearings 25 in which is journaled 110 a stud shaft 26 constituting a pivot for a substantially triangular shaped rocking lever 27 to the inner arm of which is connected the operating rod 28, while to the outer arm of said lever 27 is pivotally connected the connector straps 29, the same being also connected to the looped ends 19 of the connector member 18 hereinbefore described.

115 It will be apparent that upon operating, that is to say, reciprocating the rod 28, the lever 27 will be rocked on its shaft 26 thereby imparting corresponding movement to the walking beam 10 for the reciprocation of the pump rod B within the well.

120 The rocking lever 27 is formed with an eye 30 while mounted between the limbs of the support 9 upon the cross end piece 6 to which the support is connected is a latching hook 31, the bill of which is adapted to en- 125 130

gage in the eye 30 of the lever 27 to fasten the same against movement when the occasion requires.

It will also be apparent that the walking beam 10 can be adjusted upon the support 9 so as to properly aline the said walking beam relative to the pump rod B and also to vary the leverage of the beam should the occasion demand.

10 From the foregoing, it is thought that the construction and manner of operation of the pump jack will be clearly understood and therefore a more extended explanation has been omitted.

15 What is claimed is:

1. In a pump jack a walking beam having a centrally disposed bridge piece, a bracket secured to each end of said beam and each having its inner end formed to provide 20 an upwardly extending and inwardly inclined arm, one of said brackets having its outer end formed to provide a depending hook for connecting an operating mechanism with the beam and the other of said 25 brackets having its outer end formed to provide an upwardly extending hook for connecting the walking beam to a pump rod, and a truss rod extended over said bridge piece and having its ends connected to said 30 arms.

2. In a pump jack, a walking beam having a centrally disposed bridge piece, a bracket secured to each end of said beam and each having its inner end formed to provide 35 an upwardly extending and inwardly inclined arm, one of said brackets projecting beyond the beam and having its outer end formed to provide a depending hook, the other of said brackets having its outer end 40 formed to provide an upwardly extending hook, a truss rod extended over said bridge piece and having its ends connected to said

arms, a pump rod detachably connected to said upwardly extending hook, a connector strap detachably engaging with said depending hook, connecting straps having looped connections with the lower ends of said connector strap and a rockable lever pivotally connected to said connecting straps. 45

3. In a pump jack, a walking beam, a support therefor, a pivotally mounted triangular shaped skeleton lever having one of its arms formed to provide a loop, an operating rod connected to the looped portion of said 55 arm, a pair of connecting straps pivotally connected to the lower arm of said lever and having looped upper ends, a connecting strap depending from one end of said beam and having a looped lower end connected to 60 the looped upper end of said connecting straps.

4. In a pump jack a triangular shaped skeleton lever comprising a vertically disposed inner arm, a pair of lower arms integral with and projecting outwardly from the lower end of the inner arm, an outer arm having a looped upper end merging into said inner arm and further having a looped lower end, said outer arm extended between 70 said lower arm, a pivot pin extending through the looped lower end of the outer arm and through the outer ends of the lower arm, a walking beam, an operative drive connection between said pivot pin and one 75 end of the walking beam, means extending through said lower arms for pivotally supporting said lever, and an actuating means for said lever connected to the looped upper end of said outer arm. 80

In testimony whereof, I affix my signature hereto.

RAYMOND SPERRY.
